UNITED STATES PATENT OFFICE.

GEORGE R. STEERE, OF DETROIT, MICHIGAN, ASSIGNOR TO STEERE ENGINEERING COMPANY, OF DETROIT, MICHIGAN, A CORPORATION OF MICHIGAN.

GATE OR VALVE OPERATING SYSTEM.

Application filed February 16, 1925. Serial No. 9,630.

Apparatus for the commercial generation or distribution of gas, includes control valves or gates which must be opened and closed periodically, and in the operation of 5 water-gas generating apparatus the several valves and blast gates are necessarily operated in certain sequence and timed relation to give the desired cycle of operation. It is the common practice to effect such valve 10 operation by hydraulically operated means, the time and sequence of delivery of water pressure to such means being regulated by suitable manually operable water-pressure control valves. Such hydraulic control necessitates the installation of a water pump 15 or the like for supplying water under pressure, which water is discharged upon each operation and becomes waste.

The present invention contemplates the 20 more efficient, positive, and rapid timed operation of a valve or gate, or a series thereof, in gas manufacture and distribution, by combining steam and hydraulically operated means, whereby steam at substantially 25 boiler pressure is made available for hydraulically operating such valves or gates and the necessity for a water pump is obviated, with consequent saving in both steam and water and expense in installation. A 30 further object of the present invention is the provision of certain other new and useful features in the construction, arrangement and combination of elements, as hereinafter more fully set forth.

With the above and other ends in view, the invention consists in the matters hereinafter set forth and more particularly pointed out in the appended claims, reference being had to the accompanying drawing in which—

Figure 1 is a diagrammatic view of a control system as applied to a water-gas generating apparatus, and is illustrative of an application of the present invention;

Fig. 2 is an enlarged sectional diagrammatic view illustrative of means embodying the invention for hydraulic operation of a valve or gate; and

Fig. 3 is a view similar to that of Fig. 2 and illustrating a modification of the construction.

As indicated in Fig. 1, A indicates the usual generator, B the usual carburetor, and C the super-heater, of a water-gas apparatus, all connected and operating in the usual

manner. As is the common practice, a blast main D provides a supply of air under pressure for blowing the generator and carburetor, a branch D' leading to the bottom of the generator and a branch D² to the top of 60 the carburetor. Valves or gates E and E² for controlling the flow, are provided in these branches, and a similar valve or gate F is provided in the "back run" gas conduit G leading from the off-take pipe H at the 65 top of the super-heater C, which off-take leads to the usual water seal I from which the gas is led to the gas holder (not shown) through the main J. A cap K for closing an outlet at the top of the super-heater is 70 opened and closed in proper timed relation to the cycle of operation of the apparatus, by means of a pivoted arm K' which is operated by a piston rod K² connected to a piston within a cylinder L, and a butterfly 75 valve M in the off-take H serves to close this off-take and prevent "back-run" steam from going directly into the wash box or water seal I during the "back-run" period of operation. Oil is supplied to the top of 80 the carburetor B in the usual manner, through a supply pipe N and the flow through this pipe is controlled by a valve N'.

A steam supply pipe O has a branch O' which leads to a blower (not shown) for 85 supplying air to the main blast pipe D and in this branch is a valve O² for controlling the operation of the blower. A second branch pipe O³ leads to the off-take H of the super-heater C for supplying steam thereto 90 in the usual manner and a valve O⁴ controls the admission of steam to this branch and also to a branch O⁵ leading to the bottom of the generator A for supplying steam to the generator during the gas making period. 95 Steam supply to both branches O³ and O⁵ is controlled by a valve O⁶ in the main supply pipe O.

All of the above described parts of a 100 water-gas generating apparatus and the arrangement and operation thereof are old and well known, and form no part of the present invention, such apparatus being shown merely for the purpose of illustrating an application of the present invention to 105 gas generating apparatus embodying gates or valves operated periodically in certain timed relation, it being understood that the present invention, which relates to means for operating one or more valves or gates, 110

may be applied to any apparatus for the generation or distribution of gas or other fluid, and that the application and arrangement of the means embodying the present invention may be modified as desired, within the scope of the appended claims, to suit the conditions of the particular installation.

The present invention relates to combined hydraulic and steam pressure application to the operation of the valves or gates of a gas making or distributing apparatus or system, and comprises a cylinder 1 adjacent each valve to be operated, and in which cylinder is a piston 2 (as shown in Fig. 2) which piston is directly connected to the valve in any suitable manner, as by a piston rod 3 to open or close the valve upon movement of the piston in its cylinder. To reciprocate each piston 2 in its cylinder and open or close the particular valve connected thereto, fluid, preferably water, is admitted to or discharged from each end of the cylinder at each side of the piston therein, through pipes 4 and 5, the introduction of fluid into each cylinder through the pipe 4 serving to move the piston in a direction to open the valve, and the valve being closed by the action of fluid entering through the pipe 5. These two pipes 4 and 5 supplying fluid to each operating cylinder 1 are extended to any desired distant point and there each is connected to a separate fluid chamber of greater cubic capacity than the cubic capacity of the operating cylinder 1, preferably of about one-third greater capacity, the pipe 4 being preferably connected to the lower end of a chamber 6, and the pipe 5 to the bottom of a separate chamber 7. One of these pipes therefore forms a passage for fluid from one end of the valve operating cylinder 1 to which it is connected at one side of the piston 2 therein, to one of the fluid chambers, and the other pipe forms a passage from the opposite end of the operating cylinder to the other of said chambers, said pipes together with this cylinder and chambers forming a closed fluid circuit within which the water may be forced back and forth from one chamber to the other, to reciprocate the piston 2 in its cylinder and open or close the particular valve connected thereto.

Steam at substantially full boiler pressure is utilized to operate each valve or gate, by admitting steam to the upper end of each of the chambers 6 and 7, through separate steam pipes 8 and 9, which steam pipes lead to a reversing valve common to both pipes. When this valve control mechanism is applied to a gas generating apparatus embodying a number of valves or gates to be operated in a certain timed relation, as illustrated in Fig. 1, the several fluid chambers 6 and 7, are preferably located adjacent a central control stand (not shown) upon

which are mounted the several steam reversing valves 10, 11, 12, 13 and 14 for controlling separately, the admission of steam to the several pairs of fluid chambers 6 and 7. If desirable, any suitable mechanism (not shown) may be provided for operating these several steam control reversing valves in the proper sequence and direction to open and close the several gates or valves of the gas generating apparatus according to the desired cycle of operation of such apparatus, and preferably, a header 15 directly connected to the steam supply pipe O will be provided adjacent such reversing valves, to supply steam to these valves, and an exhaust header 16 is also provided for the several valves. These headers and nest of steam reversing valves at the control stand, may be located wherever found desirable, but preferably at a point adjacent the apparatus where the steam leads will be short so that substantially full boiler pressure will be maintained at the header 15, and as the several pairs of fluid chambers 6 and 7 will preferably be located near the header 15, with short pipes 8 and 9 containing the several reversing valves, connecting said header and chambers, steam at substantially full boiler pressure will be admitted to these chambers to exert a pressure upon the water therein and force the water from the particular chamber into which steam is admitted, and through the pipe 4 or 5 into the operating cylinder 1 to exert a direct push upon the piston 2 therein to move said piston, which movement will force the water in the cylinder at the opposite side of the piston out of the cylinder and through the other pipe into the other chamber of the pair.

By thus combining steam and hydraulic operating means, a great saving in steam is effected, as the only loss is the small exhaust from the chambers 6, 7, and through condensation therein, and a further saving is effected by this use of water as the medium of transmitting power to operate the several valves, as no water is discharged but is confined within the system, being simply forced from one chamber into the other of each pair of chambers, the supply of water on each circuit being maintained by steam condensation. There is also a decided advantage in this arrangement over the usual hydraulic control in that no pump or other means is required to maintain a constant supply of water under pressure, and cost of maintenance, operation and installation is greatly reduced.

In Fig. 1 of the drawings, the application of the present control system to a water-gas generating apparatus of the usual construction and arrangement, is diagrammatically shown, the valve O² for controlling the operation of the blower for supplying air un-

der pressure to the blast main D, being operated through the medium of the hydraulic cylinder 1 adjacent thereto and its pipe connections 4, 5 with a pair of fluid chambers 6, 7 into which chambers steam is admitted by the reversing valve 10, the particular chamber into which the steam is admitted, determining the movement of the valve O², as for instance, if steam be admitted to the chamber 6, water will be forced therefrom through the pipe 4, and open the valve. In a like manner the valve F controlling the back run pipe G opening into the bottom of the generator and the opening and closing of the butterfly valve M are controlled by the reversing valve 11, as is also the valve O⁴ controlling the admission of steam to the branches O³ and O⁵, and the valve E controlling the air blast into the bottom of the generator, and the valve E² controlling the blast into the top of the carburetor are controlled by the reversing valve 12. The reversing valve 13 in a like manner controls the operation of the cap K and simultaneously opens or closes the valve O⁶ controlling the supply of steam to the bottom of the generator and to the off-take from the superheater through the branches O³ and O⁵, and the valve N' is opened or closed to regulate the admission of oil into the top of the carburetor, by the operation of the reversing valve 14. By properly arranging the several reversing valves, they may be readily manipulated to give the proper cycle of operation of the entire apparatus, and such arrangement may be varied to suit the particular apparatus and the desired order and timed relation of operation of the several valves of such apparatus.

A modification in the construction of apparatus for operating each valve or gate, is shown in Fig. 3 and this modification consists in connecting in the system a second chamber to each chamber of the pair of chambers 6 and 7 for operating each valve, so that the liquid contained in the system will be forced by the steam pressure from one chamber into its connected chamber and from this chamber into the valve operating cylinder to operate the piston therein.

In the system previously described, there may be some leakage of water past the piston 2 in the cylinder 1 and as this piston is operated by water, there may be some corrosion and consequent sticking of the piston. To obviate these possible sources of trouble, a liquid which is of less specific gravity than water, such as oil or the like, may be employed as a medium for operating the piston 2, and this medium being of less specific gravity than water, will float upon, rise to the top or maintain an advanced position in the direction of movement of the liquid toward and into the cylinder 1 relative to the water which forms a part of the

liquid for operating the piston 2, which water may be wholly or partially the water of condensation of the steam admitted to the chambers 6 and 7 for forcing the liquid therefrom to operate the valve.

By providing a chamber 17, preferably adjacent the chamber 6 and of substantially equal or greater cubic capacity than the cylinder 1 and connecting the top of this chamber to one end of the cylinder by the pipe 4 and the bottom of the chamber to the bottom of the chamber 6 by a connecting passage 19, a body of oil may be maintained in this chamber 17 and pipe 4, this oil because of its specific gravity, floating upon or ahead of the water contained in the chamber 6. This water and oil will not mix due to the fact that the liquid of greatest specific gravity (the water) is below or at the rear of the liquid of lesser specific gravity (oil) in the direction of movement of the liquid into the cylinder. This body of oil thus not only becomes the medium through which power is applied to operate the valve, but also serves to lubricate the cylinder and piston, preventing corrosion and sticking of the piston.

In connection with the chamber 7, a similar chamber 18 is employed in a like manner, and as the volume of oil carried in each chamber 17 and 18 and connecting pipes 4 and 5 is sufficient to completely fill the cylinder 1, no water ever enters the cylinder, but this oil is forced into and out of the cylinder by the water contained in the chamber 6 and 7 when the steam pressure is turned on to the top of these water columns to force the water downward in the chambers and out into the bottom of the adjacent chamber 17 and 18, forcing the oil out of the latter chambers ahead of it, the oil, because of its specific gravity riding upon the water and not mixing therewith. Leakage past the piston 1 is prevented by the use of oil or similar liquid and corrosion prevented, and no loss of oil is sustained due to the fact that it is simply forced back and forth from the cylinder into one or the other of the chambers 17 and 18 and from the chambers into the cylinder.

Having thus fully described my invention, what I claim is:

1. In a gas apparatus having a shut-off for controlling the flow of fluid, means for operating said shut-off including a cylinder having a piston therein operatively connected to said shut-off for operating the same, separate liquid chambers located at a point distant from said cylinder and in separate open communication with opposite ends of said cylinder and each of a greater cubic capacity than the cubic capacity of said cylinder, each chamber to receive liquid from and to discharge liquid into one end of said cylinder, said cylinder being filled with

liquid and said chambers being partially filled with liquid, means for supplying steam under pressure to said chambers above the liquid therein, and means for controlling the flow of steam to said chambers.

2. In a gas apparatus having a shut-off for controlling the flow of fluid, means for operating said shut-off including a cylinder for liquid, a piston in said cylinder operatively connected to said shut-off for operating the same, a liquid chamber located at a point distant from said cylinder and in constant open communication with said cylinder at one side of the piston therein, a second liquid chamber located at a point distant from said cylinder and in constant open communication with the cylinder at the opposite side of the said piston therein, said cylinder being filled with a liquid and said chambers being partially filled with liquid the cubic capacity of each of said chambers being greater than the cubic capacity of said cylinder, whereby the movement of said piston in said cylinder in one direction will force the liquid from said cylinder into one of said chambers and movement of said piston in an opposite direction will force the liquid from said cylinder into the other of said chambers, the space in each chamber above the liquid therein being adapted to receive steam under pressure for forcing the liquid from said chamber into the cylinder, and means for controlling the admission of steam into said chambers.
3. In combination with apparatus for the generation or distribution of gas and including shut-offs for controlling the flow of fluid in such apparatus, of means for operating each of said shut-offs including a cylinder, a piston in said cylinder operatively connected to the shut-off to operate the same, a pair of water containing chambers for each cylinder located at a point distance therefrom, a water pipe connecting the bottom of each chamber with an end of said cylinder, said pipes being connected to opposite ends of said cylinder and said cylinder and pipes being filled with water, means for supplying steam under pressure separately to each chamber, and means for controlling the flow of steam to said chambers.
4. In a gas apparatus including a plurality of valves for controlling the cycle of operation of said apparatus, of means for operating said valves and controlling the

cycle of operation of said apparatus, said means including a cylinder adjacent each valve to be operated, a piston in said cylinder operatively connected to the valve to be operated thereby, a pipe leading from each end of each cylinder, a pair of chambers located at a point distant from said cylinder with one of said pipes connecting the lower end of one of the chambers of the pair with one end of the cylinder and the other pipe connecting the lower end of the other chamber of the pair with the opposite end of the cylinder, said pipes providing free open communication between said chambers and the ends of the cylinder and said chambers being partially filled and said cylinder and pipes being filled with water, the cubic capacity of said chambers each being greater than the cubic capacity of the cylinder communicating therewith to provide a steam space above the water in said chambers, steam pipes opening into the upper ends of the chambers of each pair, and means for controlling the flow of steam through said steam pipes to each pair of chambers, said steam controlling means and chambers being in proximity to each other.

5. In a gas apparatus having a shut-off for controlling the flow of fluid, means for operating said shut-off including a cylinder, a piston in said cylinder operatively connected to said shut-off to operate the same, a pair of vertically arranged chambers connected at their lower ends for the free flow of liquid from one to the other of said chambers, one of said chambers being connected at its upper end to one end of said cylinder to deliver liquid to and receive liquid from said cylinder, a second pair of vertically arranged chambers connected at their lower ends for free flow of liquid from one to the other of said chambers, one of the chambers of the pair being connected to the end of the cylinder opposite that to which the first mentioned chambers are connected to deliver liquid to and receive liquid from the cylinder, means for delivering steam under pressure to the upper end of the chamber of each pair of chambers which is connected at its lower end to the other chamber of the pair and through said other chamber to the cylinder, and means for controlling the flow of steam through said delivery means.

In testimony whereof I affix my signature.
GEO. R. STEERE
